UNITED STATES PATENT OFFICE.

EDWARD H. SEARS, OF COLLINSVILLE, CONNECTICUT.

DESIGN FOR A PLOWSHARE-BLADE.

SPECIFICATION forming part of Design No. 32,999, dated July 24, 1900.

Application filed March 6, 1900. Serial No. 7,600. Term of patent 7 years.

To all whom it may concern:

Be it known that I, EDWARD H. SEARS, a citizen of the United States of America, having residence and post-office address at Collinsville, in the county of Hartford and State of Connecticut, have invented and produced a new and original Design for a Plowshare-Blade, of which the following is a description, reference being had to the accompanying drawing, wherein the figure is a side view.

The embodied design consists of a plow-share with the point formed into a finished knife-blade, as illustrated in the drawing.

I desire to secure by Letters Patent—

The design for a plowshare-blade as herein shown and described.

EDWARD H. SEARS.
